(57) **CLAIM**

The ornamental design for a fidget spinner, as shown and described.

DESCRIPTION

FIG. 1 is a perspective view of a fidget spinner showing my new design;

FIG. 2 is a top view thereof;

FIG. 3 is a bottom view thereof;

FIG. 4 is a right side elevational view thereof;

FIG. 5 is a left side elevational view thereof;

FIG. 6 is a front elevational view thereof; and,

FIG. 7 is a back elevational view thereof.

The broken lines shown in the drawings are for the purpose of illustrating portions of the fidget spinner that form no part of the claimed design. The slanted lines shown on the circular portions of the fidget spinner represent a translucent material.
